FRANK MCKENZIE,
INVENTOR.

BY *Clem J. Kimball*

ATTORNEY.

UNITED STATES PATENT OFFICE

FRANK MCKENZIE, OF COUNCIL BLUFFS, IOWA, ASSIGNOR OF ONE-THIRD TO JOSEPH THORNELL AND ONE-THIRD TO J. CHRIS JENSEN, BOTH OF COUNCIL BLUFFS, IOWA; RAYMOND A. SMITH ADMINISTRATOR OF SAID FRANK MCKENZIE, DECEASED

ELECTRIC SAFETY-IGNITION DEVICE

Application filed March 8, 1928. Serial No. 260,088.

I have invented a new and useful electric safety ignition device in which an independent current of electricity is made to operate in conjunction with a gas valve and a 5 thermostat; and the objects of my invention are, first, to provide a safeguard against gas being turned on without ignition; second, a means for always igniting the gas when turned on; third, a means for turning off the 10 current after ignition; and fourth, a means for turning off the current of electricity when the burner is burning.

I attain these objects by the mechanism illustrated in the accompanying drawing, in 15 which—

Figure 1 is a side elevation and cross section through the burner, showing the diagram of wiring; and Fig. 2 is a plan of the entire device with the diagram of wiring left out.

20 Similar letters refer to similar parts throughout the several views.

c is an ordinary gas supply, and *v* is the usual valve supplying the gas from the gas supply *c* to the air supplied burner *n*. A lock *o* is adapted to fall over the pin *p* when the pin *p* on the valve handle *h* is turned to a 25 closed position of the valve *v*. The lock *o* is arranged to work by the magnet *q* which is in the electric circuit *t*, *s*. A lever *l* is attached

30 to the stem of the valve *v* having the handle *h* and operates with the said valve *v* on a knife blade switch of which the blades are *m* *m'*. The lever *l* when the valve *v* is closed is just out of contact with the blades *m* and *m'*. The circuit extending through the magnet *q* and through the blade switch having the lever *l* extend on through the lighting resistance *d* and through the contacts *f* *f'* which contacts *f* and *f'* are normally in contact

35 when the filaments *e* *g* are not heated. The filaments *e* and *g* having the contact pieces *f* and *f'* are made of laminated metals so that heat bends them apart and when cooled, the contacts *f* and *f'* touch each other.

40 A slight movement to open the valve *v* by turning the handle to the left throws the lever *l* in contact with the blades *m* and *m'*. This allows the current through *t* and *s* to operate on the magnet *q* to raise the latch *o* and release the pin *p* of the stem having the handle

h of the valve *v*, allowing it to open. The resistance *d* becomes heated to a sufficient white heat to ignite the gas flowing through the valve *v* and into the burner *n*. A suitable hole is placed in the burner *n* at *z* whereby 55 a flame in the burner is lighted immediately plays upon the thermostatic blades *e* and *g*, causing them to bend apart and to break the contact at the points *f* and *f'*, and so long as the burner is lit, the current in the circuit 60 *t*, *s*, will be cut off.

Upon returning the handle *h* of the valve *v* back to the right, it will close off the gas, the current of electricity will be broken as the lever *l* leaves the blades of the switch 65 *m* *m'*, and the circuit through *t* and *s* will be closed at the points *f* *f'* as the heat allows the points *f* and *f'* to come into contact. A source of electrical supply is shown in the diagram Fig. 1 from a battery *b*, but the ordinary supply is taken from the line wires of an ordinary lighting circuit. Should the lighting circuit be broken the lifting of the lock *o* by the finger can be accomplished and the pin 70 *p* of the valve stem attached to the handle *h* 75 of the valve *v* can be released and the gas lighted by a match in the ordinary way.

Should the gas become blown out by the wind or by cutting off the gas supply when the valve *v* is open the cooling of the thermostatic blades *e* and *g* will cause them to re-unite at the contact points *f* *f'* thus sending the current through the circuit *t* and *s* and through the resistance *d* relighting the gas, thus making it impossible to leave the gas 80 jet open and unlighted while current is supplied in the circuit *t*, *s*. The circuit *t*, *s* may be insulated by any heat resisting insulation and the resistance *d* is a coil made of any suitable heat resisting material, such as 85 nickel-chromium alloy or the like, and the resistance *d* is placed where it will readily ignite the gas coming from the burner *n*. Filaments *e* and *g* may be screwed onto the burner at any suitable point or may be 90 clamped to the burner so that it may be easily and temporarily removed for any purpose without disturbing the burner.

What I claim and desire to secure by Letters Patent is:

1. The combination with a gas burner and a gas valve for controlling the flow of gas to the burner, of gas igniting means including a resistance located at the burner for lighting the same, a switch in circuit with the resistance and operable by the gas valve to close the circuit when the valve is opened and to open the circuit when the valve is closed, and locking means for maintaining the valve in its closed position when there is no current in the said circuit. 70
2. The combination with a gas burner and a gas valve for controlling the flow of gas to the burner, of gas igniting means including a resistance located at the burner for lighting the same, a switch in circuit with the resistance and operable by the gas valve to close the circuit when the valve is opened and to open the circuit when the valve is closed, a locking device automatically movable to an engaging position and adapted to hold the valve closed when there is no current in the circuit, and electrically operated means in circuit with the resistance and the switch for moving the locking device to a valve releasing position when a current flows through the said circuit. 80
3. The combination with a gas burner and a gas valve for controlling the flow of gas to the burner, of gas igniting means including a resistance located at the burner for lighting the same, a switch in circuit with the resistance and operable by the gas valve to close the circuit when the valve is opened and to open the circuit when the valve is closed, a locking device automatically movable to an engaging position and adapted to hold the valve closed when there is no current in the circuit, and a magnet in circuit with the resistance and the switch and arranged to move the locking device to a valve releasing position when a current is flowing through the said circuit. 90
4. The combination with a gas burner and a gas valve for controlling the flow of gas to the burner, of gas igniting means including a resistance located at the burner for lighting the same, a switch in circuit with the resistance and operable by the gas valve to close the circuit when the valve is opened and to open the circuit when the valve is closed, a projection carried by the valve and movable therewith, a locking device arranged in the path of the said projection and automatically movable to a position for engaging the same to lock the valve in its closed position when no current is flowing in the said circuit, and a magnet in circuit with the resistance and the switch and arranged to move the locking device to a valve releasing position when a current flows through the electric circuit. 100
5. An electric lighter for a gas jet comprising, in combination, a gas jet having a fuel feed line, a manually operable control valve to regulate the flow of gas through the line, an electric circuit having a resistance coil arranged in exposed lighting proximity to the gas jet, a latch held yieldingly normally to lock said valve when closed against manipulation permitting the flow of gas through the line, a solenoid in said circuit in series with the resistance coil operable when energized to actuate said latch to release said valve to manipulation. 110
6. In combination with a gas jet having a fuel feed line provided with manipulable fuel control mechanism to regulate the flow of gas through the line, an electric gas lighter, locking means normally securing said fuel control mechanism against manipulation, automatically responsive to the operation of the gas lighter to permit manipulation of the fuel control mechanism. 120
